UNITED STATES PATENT OFFICE.

CHARLES K. SALISBURY, OF MILWAUKEE, WISCONSIN, ASSIGNOR OF ONE-HALF TO STANDARD SEPARATOR COMPANY, OF MILWAUKEE, WISCONSIN, A CORPORATION OF NEW JERSEY, AND ONE-HALF TO WILLIAM GALLOWAY COMPANY, OF WATER-LOO, IOWA, A CORPORATION OF IOWA.

SPINDLE-BEARING.

1,007,803.

Specification of Letters Patent. Patented Nov. 7, 1911.

Application filed April 6, 1910. Serial No. 553,852.

To all whom it may concern:

Be it known that I, CHARLES K. SALISBURY, a citizen of the United States, residing at Milwaukee, in the county of Milwaukee 5 and State of Wisconsin, have invented certain new and useful Improvements in Spindle-Bearings, of which the following is a specification, reference being had to the accompanying drawings.

10 My invention relates to improvements in spindle-bearings for use in cream separators or other high speed machines which require a certain amount of play in such bearings in order to take up and overcome slight in- 15 accuracies of balancing, and its object is to provide a new and improved yielding spindle-bearing for the shaft on which the bowl of the cream separator is mounted, or for shafts in other high speed mechanism, which 20 shall have a proper degree of play and in which the amount of play of such bearing may be regulated so that the same bearing may be used with shafts carrying bowls of different sizes and weight.

25 Another object of this invention is to provide new and improved oiling mechanism for such spindle bearings.

Another object of my invention is to improve such spindle-bearings in sundry de- 30 tails hereinafter set forth.

In the drawings:—Figure 1 is a side elevation, partly in vertical section, of a portion of the casing or frame of a cream separator showing my device in position. Fig. 35 2 is an enlarged detail, being a vertical section of the bearing showing, however, part of the bearing proper in elevation. Fig. 3 is an enlarged detail, being a top or plan view of the parts shown in Fig. 2. Fig. 4 40 is an enlarged detail, being a section on line 4—4 of Fig. 2. Fig. 5 is an enlarged detail, being a vertical section of the adjustable pressure ring and spring carried thereby. Fig. 6 is a top or plan view of said pressure 45 ring. Fig. 7 is a perspective view of the spring which is mounted in the adjustable pressure ring.

50 Referring to the several figures of the drawings, in which corresponding parts are indicated by like reference characters, 8 indicates the frame work or casing of the machine on which is formed the bowl casing

9. 10 indicates the separator bowl which is mounted upon the shaft 11 whose lower end is supported upon a suitable bearing, as 12, 55 mounted in the casing. The shaft may be driven in any well known manner, preferably by a worm 13 on the shaft 11 driven by worm-gear 14 which, in its turn, is driven by other gearing as by gear 15 mounted on 60 shaft 16 which may be driven in any suitable way. These parts are not further illustrated or described because they may be of any approved form and description. It will be understood, of course, that the bowl 10 65 is provided in its interior with suitable "liners" or other devices for skimming the milk. So far as the bowl itself and the skimming and delivering features, connected therewith, are concerned they may be of 70 any approved type and, forming no part of my present invention, are not illustrated or described as they will be readily understood by those skilled in the art.

17 indicates a plate which is preferably 75 separate from and secured to the bottom of the bowl casing 9 as is best shown in Fig. 1. It is preferably thus made a separate piece for purposes of mechanical construction, but of course could be formed integral with the 80 bottom of the bowl casing 9 if desired. The plate 17 is provided with a circular opening in which the other parts hereinafter de- 85 scribed are mounted, and from the central opening depends a downward projecting circular flange 18. The circular opening is provided at its top with an interior screw threaded portion 19. The lower end of the downward projecting flange 18 is turned in- 90 ward and downward at 20 so as to form a shoulder whose upper interior surface 21 slopes downward and inward. This surface may be either straight beveled, or slightly curved so as to afford substantially a ball- 95 and-socket bearing for the sleeve 22, which is the spindle-bearing proper, in connection with the other parts hereinafter described. This sleeve 22 is centrally bored with a circular opening 23 to afford a journal in which the shaft 11 revolves. At a suitable 100 distance between its ends the sleeve 22 is provided with a peripheral shoulder 24 which is rounded in section, as is best shown in Figs. 1 and 2 and, when the sleeve is in

position, supports the sleeve on the upper surface of the shoulder 21 of the flange 18 and forms substantially a ball-and-socket bearing. The lower end of the sleeve 22 is provided with a peripheral shoulder 25.

5 26 indicates a strip of felt or other oil absorbent material which in the construction shown is in the form of a tube mounted upon the exterior surface of the sleeve 22 above the shoulder 25 and extends upward around the peripheral shoulder 24 to near the top of the sleeve, as is best shown in Fig. 2. This piece of oil absorbent material is held in place in any suitable manner, as 10 by spiral spring 27 (see Fig. 2).

15 28 indicates a fixing pin which is screwed into the shoulder 24 of the sleeve 22 with its outer end projecting therefrom so as to engage a slot 29 in the inward sloping portion 20 of the flange 18, serving to hold the sleeve against rotation in the flange, but with sufficient play to allow free movement of the sleeve in said flange.

25 30 indicates a bearing-ring whose lower interior surface is beveled, as is best shown in Fig. 2, and which slips down inside the central opening of the plate 17 outside of the sleeve 22 and the felt material 26, as is best shown in Fig. 2 and when this bearing- 30 ring is held in position as hereinafter described, it coöperates with the sloping shoulders of the flange 18 to form a universal bearing for the shoulder 24 of sleeve 22.

35 31 indicates a pressure ring which is screw threaded upon its exterior so as to screw into the screw threaded portion 19 in the opening in the plate 17. The outer edge of this ring is provided with a series of scallops or indentations 32 which are adapted 40 to be engaged by a screw 33 when it is screwed into position into a suitable screw threaded opening in the plate 17 and flange 18. The screw 33 being removed, the ring 31 may obviously be screwed into any desired 45 position in the opening and then locked in place by the insertion of the screw 33.

50 34 indicates a spring which is composed of a piece of spring-wire bent in a circular form and also at opposite points, as 35-36, bent downward so that when the spring is mounted in a suitable groove 37 on the lower surface of the adjustable pressure ring 31, as indicated in Fig. 5 and in dotted lines in 55 Fig. 6, these downward projecting portions 35-36 will project below the lower surface of the ring, and, when the parts are in position, bear upon the upper surface of the bearing ring 30.

60 65 The sleeve 22 is provided with a plurality of oil openings 38 which open upon the exterior of the sleeve 22 above the shoulder 24 and pass downward and inward so as to open into a peripheral groove 39 in the interior of the sleeve. By means of these

openings and groove oil will pass from the oil-absorbent material into the interior of the sleeve and oil the opening in which the shaft is journaled.

40 indicates a plurality of oil openings 70 which open upon the exterior of the sleeve 22, above the shoulder 25, and, extending downward and inward, open into a peripheral groove 41 on the interior of the sleeve 22 near its lower end. Oil from the absorbent material will, of course, pass through these openings into the sleeve and further oil the journal bearing. Oil may be supplied to the upper openings in any appropriate manner. In the construction 80 shown, oil will be supplied to the felt by being splashed up from oil box 42 in the bottom of the casing 8 by the worm wheel 14 as is indicated in Fig. 1. In whatever way the oil is supplied to the felt, the felt 85 will become saturated, and the slight vibration of the bearing when the bowl is in rapid revolution will press the oil from the felt through the oiling openings into the interior of the bearing. 90

In putting the parts together, the sleeve 22 with the oil absorbent material in place is inserted into the opening in the plate from the top, the rounded shoulder supporting the bearing on the inward projecting portion of 95 the flange 18. The bearing ring 30 is then placed in position as above described and the adjustable ring 31 is screwed into position with the spring bearing upon the upper surface of the ring 30 so that the sleeve is held 100 in position, but with sufficient play on account of its substantial ball-and-socket adjustment to allow the slight vibration necessary in machines of this character. It will be obvious that the farther down the ring 105 31 is screwed the greater will be the tension upon the spring and the more firmly ring 30 will be pressed against the felt surrounding the shoulder 24 and the less free will be the movement of the sleeve in the 110 bearing. By this means, the spindle of course always being of the same diameter suitable to journal in the sleeve, bowls varying in weight and size may be mounted in the same bearing, the lighter and smaller 115 bowls requiring a less pressure on the spring than do the heavier and larger ones, in order to secure the proper freedom of movement. It will also be obvious in the above description that exactly the right degree of 120 pressure of the spring 34 may be secured by means of the screw threaded pressure ring, whereby the sleeve is held yieldingly against upward movement in its socket whereby the spring has a constant tendency to prevent 125 lateral movement of the spindle and to center it again when moved out of normal position by the vibrations due to the high-speed rotation of the bowl. The bearing being in place, as above described, the bowl is placed 130

in position from above with its spindle journaled in the sleeve as shown and described and the machine is ready for operation.

What I claim as my invention and desire 5 to secure by Letters Patent is,—

1. The combination of a socket-member, a sleeve extending through said socket-member and adapted to have a limited swinging motion in all directions therein, a spindle 10 journaled in said sleeve, a gear adapted to drive said spindle, an oil absorbent material surrounding the lower exposed end of said sleeve, said sleeve being provided with openings to permit oil to flow from said oil absorbent material into the interior of said 15 sleeve, and an oil receptacle in which said gear rotates, whereby oil that is placed in said receptacle is splashed by said gear upon said exposed oil absorbent material and fed 20 through said openings in the sleeve to lubricate the bearing.

2. In a spindle-bearing, the combination of a socket-member, a sleeve provided with a circumferential shoulder mounted in said 25 socket-member and adapted to have a limited swinging motion in all directions therein, an oil absorbent material surrounding said sleeve, said sleeve being provided with openings to permit oil to flow from said oil absorbent material into the interior of said 30 sleeve, a bearing ring adapted to hold said oil absorbent material in contact with said shoulder, and means for applying a variable spring pressure above said bearing ring.

3. In a spindle-bearing, the combination of a socket-member, a sleeve provided with a circumferential shoulder mounted in said socket-member and adapted to have a limited 35 swinging motion in all directions therein, an oil absorbent material surrounding said sleeve, said sleeve being provided with open-

ings to permit oil to flow from said oil absorbent material into the interior of said sleeve, a bearing ring beveled on its lower surface located upon the upper end of said sleeve above said shoulder, and adapted to hold said oil absorbent material in contact with said shoulder, a pressure ring screw-threaded into said socket-member above said bearing ring, a spring interposed between 45 said pressure ring and said bearing ring, said pressure ring being provided with scallops on its outer edge, and a pin located in the edge of such socket-member and adapted to engage any one of said scallops to prevent 50 the turning of said pressure ring.

4. In a spindle-bearing, the combination of a socket-member, a sleeve provided with a circumferential shoulder mounted in said socket-member and adapted to have a limited 55 swinging motion in all directions therein, an oil absorbent material surrounding said sleeve, said sleeve being provided with openings to permit oil to flow from said oil absorbent material into the interior of said 60 sleeve, a bearing ring beveled on its lower surface located upon the upper end of said sleeve above said shoulder, and adapted to hold said oil absorbent material in contact with said shoulder, a pressure ring screw-threaded into said socket above said bearing ring, and a spring interposed between 65 said pressure ring and said bearing ring, said spring comprising a single coil of wire held in a suitable annular groove in the 70 lower surface of said pressure ring and bent so as to project from said groove at diametrically opposite points.
